UNITED STATES PATENT OFFICE.

SIDNEY GEORGE BROWN, OF LONDON, ENGLAND.

TELEPHONY.

1,185,472.

Specification of Letters Patent. Patented May 30, 1916.

Application filed December 16, 1912. Serial No. 737,082.

To all whom it may concern:

Be it known that I, SIDNEY GEORGE BROWN, a subject of the King of Great Britain, residing at 4 Great Winchester street, in the city and county of London, England, have invented certain new and useful Improvements in and Relating to Telephony, of which the following is a specification.

10 This invention relates to telephony. In contrast with telegraphy it is of course well understood that the full possibility of duplex working in telephony is of no value since the operator at the end of any line has no 15 intention of speaking and listening at one and the same time. In telephony, therefore, only simplex working is required but it is obviously desirable to be able to converse in either direction over long distances, 20 and the chief object of the present invention is to provide, in what may be termed simplex telephony, a reliable and sensitive relay system capable of operating automatically and at any required point in the line so that 25 the distance over which speech is clearly conveyed may be considerably increased without involving great expense or necessitating frequent adjustments for the various different conditions that may arise.

30 Since a telephone station may of course be considered as a transmitting or as a receiving station according as the operator is speaking or listening, I shall refer, for convenience of description, to the two stations between which it is desired to establish communication through a relay system as stations A and B.

According to the present invention each 40 of the two stations A and B has its own relay in the line and means are provided whereby the speaking currents from either one of the two stations not only cause the local circuit of the relay corresponding to that station to become effective in magnifying the speaking currents but also cause the other station to become disconnected from its own relay and capable of receiving the aforesaid magnified currents. Each relay, which may be of any known kind suitable 45 for magnifying telephone currents, is conveniently connected across the "line" and "return" wires of its respective station through a switch arm movable between back and front stops, the switch arm being normally held against the back stop, in which

position it maintains the relay in circuit with its own station.

Electrical connections between the two relays are so arranged that when the switch arm belonging to one relay is moved so as to 60 make contact with its front stop, the connection of this relay with its own station is broken, and in addition the completion is made of a circuit that enables the magnified currents derived from the other relay to 65 reach the said station.

The movement of the switch arm of either relay into contact with its front stop is effected by an electrical device or devices, preferably deriving current from the other 70 relay, as hereinafter described.

In order that the said invention may be clearly understood and readily carried into effect the same will now be described more fully with reference to the accompanying 75 drawings in which:—

Figure 1 represents diagrammatically two telephone relays with their electrical connections and coöperating devices for carrying out the invention. Fig. 2 represents a modification of the system shown in Fig. 1. Fig. 3 is an end elevation and Fig. 4 a side elevation of one of the electrical devices hereinbefore referred to as being used in effecting the actuation of the switch arm. Fig. 5 is a diagram of a modification of part of the system shown in Fig. 1, and Fig. 5^a is a detail of construction hereinafter described. Fig. 6 represents diagrammatically a further modified system in which the two relays are 80 situated at some distance apart in the line of communication between the two stations. Fig. 7 represents diagrammatically a modification of the system shown in Fig. 1, and Fig. 8 represents a modification of the system shown in Fig. 7. 85

Referring first to Fig. 1, A' is the relay corresponding to station A and connected therewith by the wires a a', and B' is the relay corresponding to station B and connected therewith by the wires b b'. The connection of the wire a to the relay A' is by way of the condenser A², and of the wire a' by way of the switch arm A³; similarly the connection of the wire b to the relay B' is 100 by way of the condenser B², and of the wire b' by way of the switch arm B³. a⁰, a^x are the front and back stops respectively of the switch arm A³, and b⁰, b^x the front 105 and back stops of the switch arm B³. The 110

local circuit of the relay A' includes a local battery A⁴, an indicator A⁵, and the primary of an autotransformer A⁶; similarly the local circuit of the relay B' includes a local battery B⁴, an indicator B⁵, and the primary of an auto-transformer B⁶. The secondary terminals of the auto-transformer A⁶ are connected by way of the leads a² a³ to the wire b and the front stop b⁰ respectively; similarly the secondary terminals of the auto-transformer B⁶ are connected by way of the leads b² b³ to the wire a and the front stop a⁰ respectively. In the local circuit of the relay A' there is connected, in parallel with the primary of the auto-transformer A⁶, the winding of an electromagnet A⁷ in series with a condenser A⁸; the electromagnet A⁷ has for its armature a resilient reed A⁹ on which rests one end of a balanced arm A¹⁰. The reed A⁹ and balanced arm A¹⁰ form part of a circuit including a battery A¹¹ and the winding of an electromagnet A¹²; they may also be shunted by a condenser as shown by A¹³. The electromagnet A¹² is so related to the switch arm B³ that the latter serves as armature to it. The electromagnets A⁷ and A¹² constitute the electrical devices hereinbefore referred to as serving to control the movements of the switch arm. The connections of the parts B⁷, B⁸, B⁹, B¹⁰, B¹¹, B¹² and B¹³ will be understood from the foregoing description and need not be described in detail. So long as the reed A⁹ is stationary the steady current from the battery A¹¹ energizes the electromagnet A¹² with the result that the latter maintains the switch arm B³ in contact with its back stop b^x; similarly with regard to the reed B⁹. These reeds A⁹ B⁹ are stationary so long as neither of the operators at the two stations A and B is speaking. Suppose now that the operator at station A speaks into his transmitter. The relay A' at once becomes operative, and the variable currents in the local circuit of this relay cause the resilient reed A⁹ to vibrate, with the result that the steady current from the battery A¹¹ becomes destroyed or upset, whereupon the electromagnet A¹² ceases to hold the switch arm B³ against its back stop b^x. The switch arm B³ therefore breaks the line circuit through the relay B' and makes immediate contact with its front stop b⁰ and thereby completes the circuit of the station B with the secondary terminals of the transformer A⁶, the primary of which transformer has of course been traversed by the local currents of the relay A' simultaneously with the passage of these currents through the winding of the electromagnet A⁷. When the operator at station A ceases speaking, the steady current from the battery A¹¹ through the winding of the electromagnet A¹² is restored and the switch arm B³ therefore becomes at-

tracted back to its position of contact with its back stop b^x. If the operator at station B now speaks, a precisely similar sequence of events takes place. It is important to observe that the circuit of one station is automatically prepared for the reception of currents from the relay of the other station by the currents derived from the relay of the latter station.

The means shown in Fig. 1, for actuating the switch arm A³, B³, are to be considered more with reference to their principle of action than to their construction; for instance, it is necessary that the contact of the switch arms with their front stops should take place sharply but without "chattering", and for this purpose the actual contact surface of the switch arm may be constituted by the free end of a blade spring attached to the said arm.

In the modification shown in Fig. 2, the reeds A⁹ B⁹ and the balanced arms A¹⁰, B¹⁰, normally serve to shunt the windings of the electromagnets A¹² B¹² relatively to the batteries A¹¹, B¹¹, resistances A^{11x}, B^{11x}, being provided to limit the normal current from the batteries. When however either reed vibrates, the circuit through it is, for practical purposes, destroyed temporarily, and the full battery current traverses the corresponding electromagnet and thereby causes its switch arm to be actuated. Since in Fig. 1 the electromagnet is normally operative, whereas in Fig. 2 it is normally inoperative, it must of course be so placed relatively to the switch arm as to influence this arm oppositely in the two cases.

As regards the electromagnetic vibration devices A⁷, A⁹, A¹⁰ and B⁷, B⁹, B¹⁰, it may be observed that the electromagnet winding of either or both of them might be on the "line" side of the corresponding relay instead of in the relay local circuit, but the method of connection already described is preferable since the currents available are the magnified currents of the relay. In a modified arrangement the vibration devices might be dispensed with in Fig. 1 and the respective relay local circuits themselves include, in series with them, the windings on the electromagnets, provided the relay local current were in each case strong and steady enough during the periods of inaction of the relays. The arrangements described with reference to Figs. 1 and 2 are however preferable.

One constructional form of the vibration devices is shown in detail in Figs. 3 and 4 and will now be described. The core of the electromagnet A⁷ comprises the magnetized steel base A^{7xx} carrying at its poles the upwardly inclined pole pieces proper the ends of which converge under the free end of the resilient reed A⁹. The reed is of spring steel having a cut-away portion

to impart resiliency and is held down by screws upon a knife edge A¹⁴. The free end of the reed carries a small disk or plate of carbon and the riding end A¹⁵ of the balanced arm A¹⁰ is preferably gold, although other material, for instance, osmium-iridium alloy, may be used. The balanced arm A¹⁰ is carried by a rod or plate A¹⁶ supported horizontally by wires or fibers 10 A¹⁷. One wire or fiber passes over a pulley and is attached to a spring A¹⁸ and the other is secured to the point of an adjusting screw A¹⁹ by means of which the torsion of the wires or fibers and hence the sensitiveness of 15 contact of the arm A¹⁰ with the carbon on the reed A⁹ can be accurately adjusted. It is desirable, for the efficient action of the switch arms that control the relay circuits, that these arms should move away from 20 their back stops suddenly and return gradually and it will be understood that a vibration device having a balanced contact and other parts constructed and arranged as above described will bring about the result, since the balanced contact will very 25 quickly respond to vibrations and will be somewhat sluggish in coming to rest. This sudden movement of the switch arms in one direction and their more gradual movement 30 in the opposite direction may however be obtained in other ways.

The electromagnetic vibration devices above described operate by practically destroying the electric circuit normally maintained through the reeds and balanced arms. The actual breaking of such a circuit is not however imperative and in some cases may be detrimental since a sustained noise or musical note in the line may cause the 35 vibration device to operate. A form of the device which is not subject to this defect is represented in Fig. 5. The electromagnet A⁷ acts upon the reed A⁹ as in the prior construction, but this reed carries a contact 40 piece forming part of a microphone A²⁰ through which the circuit of the battery A¹¹ is completed; the battery circuit also includes the coil A^{12x} which is suspended in a strong magnetic field and carries the 45 switch arm B³, thus serving the purpose of the electromagnet A¹² in Fig. 1. A comparatively strong battery current normally traverses the microphone A²⁰ and the coil A^{12x}, and the latter is adjusted so that under 50 normal conditions the switch arm B³ presses against its back stop. When however the reed A⁹ is rapidly vibrated in response to speaking currents, the average strength of the current traversing the microphone, and 55 hence also the coil, is considerably reduced; this is a well known effect in telephone microphones and is here utilized to reduce the 60 rent in the coil A^{12x} so much that the coil moves and carries the tongue B³ into contact with its front stop. The advantage of

this microphonic form of electromagnetic vibration device is that a sustained note or similar disturbance in the line merely produces a change in the strength of the current normally traversing the microphone 70 and therefore merely alters the value from which the current strength falls when the reed vibrates. The switch arms carried by the suspended coils may advantageously be carried after the manner of what are sometimes called jockey tongues, that is to say each tongue, say the tongue B³ for example, is rotatably mounted upon the coil A^{12x} by a pin A^{14x} between the head of which and the boss of the tongue is situated a spring 75 A^{15x} as seen clearly in Fig. 5^a. The spring A^{15x} causes sufficient friction between the underside of the boss on the tongue B³ and top of the coil to make the coil and tongue move together about their common axis of 80 oscillation so long as no obstruction is offered to the tongue. When however the tongue is obstructed in its movement, the coil can continue to move in the same angular direction but immediately the coil commences to move in the opposite direction the tongue moves with it. 85

Hitherto it has been assumed that the two relays and their coöperating devices are situated at one relay station situated 90 somewhere between the two terminal stations A and B, and it is natural to suppose that this relay station would be situated about midway between them. Under such circumstances, any noises or disturbances 95 between one terminal station and its relay would be superimposed upon the speaking currents and be magnified proportionately by the relay before being sent on to the distant station. If, however, the two relays 100 were separated, each being placed comparatively near its own station, the noises or other disturbances magnified by it, and superimposed upon the speaking currents, 105 would be only those arising from the reduced length of line between the said station and its relay. In other words the noises or disturbances arising in the portion of the line between the two separated relays would not be magnified by either of them—that is to say, so far as the relays are concerned this intermediate part of the line would be illuminated. A relay system adapted to work in this manner is shown 110 in Fig. 6. The dotted horizontal lines represent the intermediate portion of line between the relays. The electrical connections will be readily understood by inspection of the drawing and are for the most part similar to those of Fig. 2. It is however to be observed that there is a direct connection, by way of condensers, from the wire a of station A to the wire b of station B; also a direct connection, by way of condensers and the switch arms A³ B³, from 115 120 125 130

the wire a' of station A to the wire b' of station B. One end of the secondary of each of the autotransformers A^6 B^6 is connected to the line, and the other end to the back-stop of a switch arm, as it was in the arrangement shown in Fig. 2; this back-stop connection, however, is preferably effected through a second switch arm A^{3x} or B^{3x} , respectively, as shown. In parallel with the primary of the auto-transformer A^6 , which forms part of the local circuit of the relay A' , is a circuit containing the condenser A^8 and the energizing winding of a vibration device A^{7x} ; the local circuit of this vibration device normally serves as a short circuit to the local battery A^{11} , as in the arrangement shown in Fig. 2. The poles of the battery A^{11} are also connected to electromagnets a^{13} , a^{13x} of which the electromagnet a^{13} is adapted for coöperation with the switch arm A^3 , and the electromagnet a^{13x} adapted for coöperation with the switch arm A^{3x} . The other ends of these windings or coils are connected across the line as shown. Similar remarks apply to the switch arms B^3 B^{3x} , the electromagnets b^{13} , b^{13x} , the battery B^{11} , and the vibration device B^{7x} . The batteries A^{11} , B^{11} are, however, opposed as regards the direction of the current supplied by them to the line, and the electromagnets a^{13} , a^{13x} , and b^{13} , b^{13x} , are polarized, the result being that the energizing of a^{13} , a^{13x} by current from the battery A^{11} does not move the switch arms A^3 , A^{3x} , nor the energizing of b^{13} , b^{13x} , by current from the battery B^{11} move the switch arms B^3 , B^{3x} . Current from the battery A^{11} , however, in energizing b^{13} , b^{13x} by way of the intermediate portion of the line between the two relays, causes the switch arms B^3 , B^{3x} , to be actuated; and current from the battery B^{11} , in energizing a^{13} , a^{13x} , causes the switch arms A^3 , A^{3x} to be actuated.

45 The operation is as follows: When the operator at station A speaks into his transmitter, the relay A' is actuated and the local current from the battery A^4 actuates the vibration device A^{7x} ; the short circuit which this vibration device normally offers to the battery A^{11} , is, therefore, destroyed, and the current from the battery now traverses the windings of the electromagnets a^{13x} , b^{13x} , b^{13} , and a^{13} , but owing to the particular manner in which these electromagnets are polarized, only b^{13} , b^{13x} , are effective in moving the corresponding switch arms B^3 , B^{3x} . By the moving over of these switch arms, the line b' is placed in circuit with the secondary of the auto-transformer A^6 , and the auto-transformer B^6 is prevented from acting as a short circuit to the currents from the said auto-transformer A^6 . The latter transformer therefore passes on the magnified currents from the

relay A' to the distant station B. It is, of course, understood that simultaneously with the actuation of the vibration device A^{7x} by current from the local circuit of the relay A' , the primary of the auto-transformer A^6 is energized, and hence also the secondary of this transformer. When the operator at station A ceases speaking the parts return to their normal positions. When the operator at B speaks a sequence of operations similar to those already described will take place, as will be understood. The secondary of the auto-transformer B^6 will be placed in circuit with the wires a a' of station A, since the switch arms A^3 , A^{3x} , will be actuated, but not the switch arms B^3 , B^{3x} .

70 The type of relay employed as the relay A' or B' may be any convenient form of magnifying relay suitable for telephonic work, such as the relay described in the specification of my prior United States Patent No. 1,048,443 of December 24, 1912, or one similar to the relay therein described but having a granular carbon cell to perform its microphonic functions.

75 It has already been stated that the vibration devices, instead of being worked by current derived from the local circuit of their respective relays, might be worked by the line currents. Since the line currents are, of course, available at any point in the line, a natural development of this modification is the placing of the vibration device at some distance from its corresponding relay; 80 it might for instance be placed close to the transmitting station, and in fact be connected across the transmitter itself. One arrangement of this kind is shown in Fig. 7, and will now be described. The energizing circuit of the vibration device A^{7x} together with a condenser A^8 are connected directly across the transmitter or across the line near the transmitting station and the derived circuit of the device includes the battery 85 A^{11} and the electromagnet C. This electromagnet normally holds a switch arm C^x against its back stop c' , and thereby keeps the circuit of a second battery C' broken. When, however, speaking currents traverse 90 the vibration device, the steady current from the battery A^{11} is broken and the switch arm C^x makes contact with its front stop c , thereby causing the second battery C' to send a steady current along the line. This 95 steady battery current, which lasts as long as speaking currents are traversing the vibration device A^{7x} , energizes the electromagnet A^{12} so that the latter causes the switch arm B^3 to disconnect the relay B' 100 from the line and place the distant station B in circuit with the secondary of the auto-transformer A^6 . Similarly when speaking currents from station B traverse the vibration device B^{7x} , the electromagnet D ceases 105

to attract the switch arm D^x and a steady current from the battery D' is sent along the line to the electromagnet B^{12} , and the switch arm A^3 is attracted over against its front stop a^o thus disconnecting the relay A' from the line and connecting the distant station A with the secondary of the auto-transformer B^o .

In the system above described with reference to Fig. 7, and also in that about to be described with reference to Fig. 8, the line and return wires are normally "dead," since the constant presence of a steady current in them would keep the switch arm electro-magnets constantly energized. The principle underlying the system shown in Fig. 7 and distinguishing it from the system shown in Fig. 1 may advantageously be modified as shown in Fig. 8 which will be understood for the most part merely by inspection. The right and left hand ends of this figure represent devices and connections operating similarly to those shown in Fig. 7, but it is important to notice that the batteries C' and D' must be oppositely connected across the transmitters or across the line near the same, so that if one battery may be said to send a plus current along the line the other sends a minus current. The electromagnets A^{12} and B^{12} at the relay station are polarized, the result being that the current from either battery, C' or D' , traverses the windings of both electromagnets but only one of the latter is operative in attracting its switch arm. For example current from the battery C' causes the electromagnet A^{12} to attract the switch arm B^3 against its front stop b^o but leaves the electromagnet B^{12} inoperative in its effect upon the switch arm A^3 . The set of apparatus and connections illustrated in the mid-part of Fig. 8 might be employed several times at intervals between the end stations, and it will be understood that a single vibration device at each station would be effective in operating all the intermediate relay stations in the same manner as it operates the single relay station shown in the figure.

In order that the operator at one station may speak to the operator at a distant station, he must first draw the distant operator's attention by sending a current which will bring about the ringing of a bell or the lighting of a small lamp, as is customary in ordinary telephony. To enable a signaling current to be sent from one station to another in my simplex relay system, I may connect up the two stations through inductances as shown for example by E E' in Fig. 2, or F F' in Fig. 8. A steady current could then be sent from one station to the other; this current would not affect the relays owing to the presence of the condensers; also the connection between the two stations would have no effect during the

actual transmission of speech, since the inductance in this connection would act as a complete break so far as speaking currents are concerned. As regards Figs. 7 and 8 it will be understood that varying currents such as those produced by speaking are prevented from traversing the circuits of the batteries C' and D' owing to inductances in series in these circuits, and that they are prevented from traversing the windings of the electromagnets A^{12} and B^{12} owing to the inherent high self-inductance of these electromagnet windings.

What I claim and desire to secure by Letters Patent of the United States is:—

1. In a telephonic relay system connecting two stations, a relay electrically connected with the one station, a relay electrically connected with the other station, a switch acting in conjunction with each relay to close the circuit between the relay and its own station, and electrical means set in action by relay-magnifying speaking currents whereby the actuation of the relay pertaining to one station simultaneously causes the switch in the circuit of the relay of the other station to automatically break the connection between that station and its relay, and establish a path for transmission of the aforesaid magnified currents to said station.

2. In a telephone system connecting two stations, relay apparatus comprising for each station a relay electrically connected to the station, a switch normally closing the electrical connection, an electrical device operable by magnified speaking currents derived from the relay, electromagnetic means adapted to operate the other station-to-relay connecting switch under the control of the said electrical device, and means whereby movement of the latter switch from its normal position enables the aforesaid magnified currents to be transmitted to the station corresponding to said switch.

3. In a telephone system connecting two stations, relay apparatus comprising for each station a relay electrically connected to the station, a switch arm forming part of the electrical connection, front and back stops co-operating with said switch arm, the back stop being connected to the line side of the aforesaid relay and the front stop to the local side of the relay of the other station, means keeping the switch arm normally in contact with its back stop to complete the aforesaid electrical connection, and means whereby when either relay is being actuated the magnified speaking currents derived from it cause the switch arm to the other relay to move over from its back stop to its front stop and to be held against the latter.

4. In a telephone system connecting two stations, relay apparatus comprising for each station a relay electrically connected

to the station, a switch arm forming part of the electrical connection, front and back stops coöperating with said switch arm, the back stop being connected to the line side 5 of the relay and the front stop to the local side of the relay of the other station, an electromagnetic vibratory device operable by the magnified speaking currents derived from the relay, an electromagnetic device 10 for controlling the switch arm of the other relay, and a battery and electrical connections between the two electromagnetic devices.

5. In a telephone system connecting two 15 stations, relay apparatus comprising for each station a relay electrically connected to the station, a switch arm forming part of the electrical connection, front and back stops coöperating with said switch arm, the 20 back stop being connected to the line side of the relay and the front stop to the local side of the relay of the other station, an electromagnetic vibratory device, a transformer electrically connecting the local circuit of 25 the relay with the said vibratory device, an electromagnetic device for controlling the switch arm of the other relay, and a battery and electrical connections between the two electromagnetic devices.

30 6. In a telephone system of the kind hereinbefore described, the combination with a relay electrically connected to each station, a switch arm forming part of such connection, and front and back stops for coöperation 35 with said switch arm, of an electromagnet coöperating with said switch arm, a battery in the electromagnet circuit, and means depending for operation upon the magnified speaking currents derived from the other 40 relay for destroying the steady current of the battery.

7. A telephone system consisting in the combination with the telephonic transmitting and receiving apparatus at each terminal 45 station, of a magnifying relay in electrical connection with one station, a magnifying relay in electrical connection with the other station, electrical means whereby the

magnified speaking currents resulting from the actuation of either relay cause the station of the other relay to be automatically disconnected from its own relay and capable of receiving the magnified currents from the first relay, and inductances forming a through connection between the stations for 55 ringing-up purposes.

8. In a telephone system connecting two stations, relay apparatus in respect of each station, comprising a relay electrically connected to the station, a switch arm and a 60 back stop forming part of the electrical connection, a front stop electrically connected with the relay of the other station, a vibration device electrically operated by the relay local current, a polarized electromagnetic device coöperating with the switch arm, a local battery having the circuit completed through the vibration device and the electromagnetic device, and electrical connections between the polarized electromagnetic devices of the two stations, the polarization being such that the local battery current of either station renders operative only the electromagnetic device of the other station. 75

9. In a telephone system connecting two stations, relay apparatus comprising for each station a relay electrically connected to the station, a switch arm forming part of the electrical connection, front and back 80 stops coöperating with said switch arm, the back stop being connected to the line side of the relay and the front stop to the local side of the relay of the other station, a microphonic device operable by the magnified 85 speaking currents derived from the relay, an electromagnetic device for controlling the switch arm of the other relay, and a battery and electrical connections between the two devices. 90

In testimony whereof I affix my signature in presence of two witnesses.
